United States Patent Office

Des. 187,818
Patented May 3, 1960

187,818

NUT

David W. Grimm, La Habra, Calif., assignor to Kaynar
Mfg. Co., Inc., Rivera, Calif., a corporation of California

Application January 12, 1959, Serial No. 54,143

Term of patent 14 years

(Cl. D54—9)

Figure 1 is a perspective view of a nut embodying my new design.

Figure 2 is a top plan view of the nut shown in Figure 1.

Figure 3 is a side elevation of the nut shown in Figure 1.

I claim:

The ornamental design for a nut, as shown.
